SKILES E. TEST, OF INDIANAPOLIS, INDIANA

APPARATUS FOR WARMING AND CLEANING ARTIFICIAL POOLS

Application filed December 5, 1931. Serial No. 579,265.

This invention relates to a process of and apparatus for warming and cleaning an artificial swimming pool and the like.

The chief object of this invention is to render a pool of the character set forth clean and comfortable by the provision of suitable means so that a minimum flow of water is required to secure such cleanliness and comfortableness.

10 The chief feature of the invention consists in the formation of a peripherally enveloping, or substantially peripherally enveloping, channel adjacent the pool and into which the surface water and surface débris is discharged automatically by the wind passing over the surface of the pool when not occupied or by the rise in level of the pool or motion of the surface water in the pool due to the presence of a person, or persons, therein. The water which flows from the pool into the draining channel is discharged into a sump which collects such surface débris, and separates the same from the water that has been the vehicle for removing the same from the pool. This surface water is warm and it is supplied to the bottom of the pool near the center thereof, so that it will pass upwardly through the pool contents and serve to warm the bottom of the pool, thereby rendering the pool more comfortable and at a more uniform temperature throughout the various water levels thereof.

35 The full nature of the invention will be understood from the accompanying drawing and the following description and claims:—

In the drawing, Fig. 1 is a vertical longitudinal sectional view of an artificial pool of rectangular outline with the apparatus diametrically associated therewith.

40 Fig. 2 is a top plan view of the pool.

In the drawing, 10 indicates the end walls of an artificial swimming pool of rectangular cross section, 11 the side walls and 12 the bottom which preferably is inclined so as to provide different depths of water in the pool, although the bottom may be level if desired. Each of the walls has an outwardly and upwardly inclined surface 13 terminating in a level line division 14. Extending outwardly and downwardly therefrom is an inclined wall

15 which forms one side of a channel having the opposite wall 16. The bottom of the channel is indicated at 17 and the bottom of the channel leads to suitable drains 18. These drains are definitely placed or arranged and are at the lowerst points of the channel. All of the drains are connected by pipes 19 to a sump 20 and the level of the water in the sump is indicated at 21. It may be any desired level. All of the débris carried over from the pool into the channel collects in the sump and access is had thereto from the top by removing cover 22 so that said surface debris may be readily removed from the sump. A suitable screen 23 or other equivalent separator, may be employed to permit the water which has carried the débris to the sump to pass through the sump and to a filter 24. Herein a pump 25 is interposed between the sump and the filter. However, the sump may discharge by gravity to the filter, if desired.

The filter also includes a fresh water supply line 26. This is for make-up purposes, due to evaporation and the like, resulting in loss of water in the pool. The filter includes the discharge 27 which supplies a header 28, in turn connected to a plurality of conduits 29, each of which discharges as at 30 along the longitudinal center of the bottom of the pool and adjacent the central portion thereof. A plurality of said outlets or discharges insures a longitudinal distribution of the water which has passed through the filter.

It will be apparent that when the peripheral edge 14, constituting the partition between the pool and the channel, is peripherally level, that no matter which way the wind blows, the water will follow the wind and carry with it the surface débris. The wind will move this surface water and the water passing over this line division will gradually clear the surface of the pool. The inclination of the approach to the line division is important and materially facilitates or assists in the discharge of the débris from the pool.

Since the surface water is that which is discharged, it will be evident that this water, which is the warmest, would result in the

pool gradually becoming chilled so that it is highly desirable for this water to be returned to the pool for two reasons. One is to retain the heat of the discharged water and return it to the pool and return it in such a way that it will retain uniformity of temperature throughout the pool contents, and a second reason is that this surface water discharged, as aforesaid, is considerable and the pool is constantly discharging. Therefore, this water should be returned to the pool rather than require the addition of new water which will usually be cold.

If the pump is not in use—for example, when the pool is not in use—the automatic action of the wind in cleaning the surface of the pool will cease after the water decreases to a certain level in the pool with reference to the wind velocity and no further cleaning action will occur. The pump is usually in operation at all times while the pool is in use. This is to insure a full pool and constant cleaning.

Inasmuch as considerable surface débris collects around the pool and is tracked into the same, there is provided around the pool a walk 30 and herein the same is inclined as illustrated and discharges to the drainage channel, the face 16 thereof serving the same purpose for this drainage as the face 15 serves for the pool drainage. This side walk also receives the splashings from the pool in the use of the pool and this splashing, together with all surface débris that accumulates on the side walk, is collected in the sump from which it can be removed and is returned to the pool. The aforesaid débris consists chiefly of leaves, sticks, scum, dirt loam, and the like.

The present arrangement which utilizes the wind when it is from any direction, insures that the power for moving the débris from the surface of the pool is provided by nature and the only power required is that necessary to return the small amount of water to the pool, which has theretofore been splashed or blown therefrom.

It will be perfectly obvious that if the pool were not substantially peripherally provided with a drainage channel and that the collection channel was only provided at one end or two opposite ends or along one or two sides that, if the wind were in an opposite direction, the pool would not be cleaned by water flowing from the pool to a collection chamber, unless a pump of enormous capacity were utilized to not only supply sufficient water but also to oppose the force of the wind.

The present invention, therefore, utilizes fully any wind that may be available and

thereby secures automatic cleaning of the surface of the pool and a very small capacity motor and pump may be utilized solely for returning the cleaned water to the pool for replenishment.

The invention claimed is:—

1. In an artificial swimming pool, the combination of a pool body, a vertically exposed channel peripherally enveloping the same at the upper edge of the body, a partition between the pool body adjacent the side wall and the channel, and having oppositely inclined walls forming a level line division between the pool side and the channel, each wall being of appreciable width, one wall of the partition forming a wall of the channel.

2. In an artificial swimming pool, the combination of a pool body, a vertically exposed channel peripherally enveloping the same at the upper edge of the body, a partition between the pool body adjacent the side wall and the channel, and having oppositely inclined walls forming a level line division between the pool side and the channel, each wall being of appreciable width, one wall of the partition forming a wall of the channel, and a walk around the pool and inclined toward the pool and peripherally discharging into the channel.

3. In an artificial swimming pool, the combination of a pool body, a vertically exposed channel along each side of the pool, a partition between the pool body at each side of the pool, said partition having oppositely inclined walls of considerable width and forming a level line division between the adjacent pool side wall and the channel whereby any wind upon the surface of the pool will cause surface debris to pass over the pool at the far side of the pool with reference to the direction of the wind.

4. In an artificial swimming pool, the combination of a pool body, a vertically exposed channel along each side of the pool, a partition between the pool body at each side of the pool, said partition having oppositely inclined walls of considerable width and forming a level line division between the adjacent pool side wall and the channel whereby any wind upon the surface of the pool will cause surface debris to pass over the pool at the far side of the pool with reference to the direction of the wind, and a walk at each side of the pool and inclined toward the pool and discharging at its lower edge substantially along the complete line thereof into said channel.

In witness whereof, I have hereunto affixed my signature.
